Eliphilet Mett.

8790 X

Letters Patent

The Schedule referred to in these Letters Patent and making part of the same containing a description in the words of the said Eliphilet Mett, himself of his improvement in the Plain plate or top book stove, having an interior box, a return kettle flue and its inlet for fuel at the end.

Whereas incoconveniences has accrued in the use of said stove on account of the waste of fuel and the unequal distribution of heat in the box, therefore certain improvements have been introduced which consist— 1. In combining with said interior box doors made of tin or other reflecting material, in place of cast or sheet iron doors; or 2. in dispensing with said interior box altogether, and in combining in place thereof, with the furnace and kettle flue, exterior side bake ovens, and roasters or other culinary instruments in tin or other reflecting material, each having of desired, aperture governed by valve, on the upper or under side, or on both for the admission of air, when necessary for regulating the temperature or impinging the flavor; which combinations may be effected by adapting to each other the sides of said stove and the face of said instruments, in form, size and structure, so as to make when combined a regular fit; and by connecting the two by hanging the latter aside the former, like doors so as to open and shut, and ship and unship, or by providing for the adjustment of the latter aside the former, by means of rollers, ways, catches, hooks, or any other fixture preferred for the purpose. 3. In combining in said stove with the return kettle flue and exterior side ovens aforesaid if desired, a furnace more or less connected by receding so much of the side plates, as lie below the return flue, and thus forming a rest for the bottom plate thereof; and also for a lining if in

if in use, as well as for keeping the side doors from touching the furnace. 4. In combining in said stove, with said exterior side doors, return flue and furnace, whether contracted or not, a brick or other nonconducting lining for the bottom and end of the furnace, and if desired, for the sides of the return flue, or for both: the lining of the flue may consist of a mere boat of mortar held in place by numerous small points, projected from the side plate; and in further combining with said exterior side doors an end door having vertical judgons, a fixed latch, and being fastened by the raising and falling of said door, in the cast sockets provided therefor; and if desired, in further combining with said doors a projecting hearth plate with a raised margin, fitted for the reception of the infus, between said hearth plate and end a parallel grated plate for receiving coal for boiling.

5. In combining in said stove with said exterior reflecting side doors and furnace, whether contracted or not, side plates, pierced for the escape of steam from the boxes that adjoin them to the return flue. 6. In combining in said stove with said exterior reflecting side doors and furnace, a return flue, having the bottom plate thereof so pierced and governed by valves, as to direct the flame to, or from a contained kettle at pleasure. 7. In combining in said stove with said exterior reflecting side doors, an elongated return flue, that is, a flue that projects beyond, or overhangs the furnace, either at one or both ends, said flue having its bottom plates, if desired pierced and governed by valves, as aforesaid.—

8. In combining in said stove with said exterior reflecting side doors, guard plates, either fixed or movable in the form of blinds, for checking, equaling and controlling the lateral relation from the furnace, said guard plates being attached either to the stove, or to the side doors connected therewith.

9. In combining in said reflecting side door, a central slot

8790X

floor, centered on a horizontal base in such manner that by
turning the same, the bottom of the article resting on said
floor can be more or less exposed to the direct heat from the
side of the furnace.

For further information, reference may be had to
the explanations and drawings connected herewith.
Claim. I claim as my invention, each and all of the various
improvements in said plate or box stove, and especially
each set forth in each and all of the above enumerated
combinations, together with the use to which the same be
put or may be hereafter applied.

Witnessed
